UNITED STATES PATENT OFFICE.

FRANCIS H. RICHARDS, OF SPRINGFIELD, MASSACHUSETTS, ASSIGNOR TO THE AMERICAN BUTTON FASTENER COMPANY, OF NEW BRITAIN, CONN.

BUTTON-FASTENER-SETTING MACHINE.

SPECIFICATION forming part of Letters Patent No. 341,054, dated May 4, 1886.

Application filed September 14, 1885. Serial No. 177,085. (No model.)

To all whom it may concern:

Be it known that I, FRANCIS H. RICHARDS, a citizen of the United States, residing at Springfield, in the county of Hampden, State 5 of Massachusetts, have invented certain new and useful Improvements in Button-Fastener-Setting Machines, of which the following is a specification.

This invention relates to improvements in 10 machinery especially adapted for setting or inserting into shoe uppers or fabric that kind of button-fasteners known in the market as "Kempshall's One-Prong-Button Fastener;" and it is in the nature of an improvement on 15 a machine for the same purpose described in United States Patent No. 310,541, granted to me January 6, 1885.

The invention has for its object to furnish a more convenient and efficient machine of its 20 class, having button-feeding appliances; and it consists in the devices and combinations hereinafter set forth.

In the drawings accompanying and forming 25 a part of the specification, Figure 1 is a front elevation of a machine embodying my improvements. Fig. 2 is a side elevation, on a reduced scale, of the machine, drawn in projection with Fig. 1. Fig. 3 is a vertical section through the machine from front to rear, 30 showing the parts at the beginning of the fastener-setting operation. Fig. 4 is a view similar to Fig. 3, showing the parts at a later stage of the operation. Fig. 5 is a view similar to Figs. 3 and 4, but on a larger scale, showing 35 the parts at the close of said operation. Fig. 6 shows a part of Fig. 5, with the setting-die returning to its upper position. Fig. 7 is a horizontal section in line *a a*, Fig. 5. Fig. 8 is a front view of the button-reservoir. Fig. 40 9 is an end view of the same as seen from the left hand in Fig. 8. Fig. 10 is a top view of the reservoir. Fig. 11 is a rear view of the same. Figs. 12, 13, and 14 are respectively sections in lines *b c d*, Fig. 8. Fig. 15 is a front 45 view of a modified construction of the reservoir. Fig. 16 is a top view of the same. Figs. 17, 18, and 19 are respectively sections in lines *e f g*, Fig. 15. Fig. 20 is a perspective view of the follower shown in Figs. 15, 16. Fig.

21 is a side view, on a reduced scale, of the 50 complete button-fastener magazine. Fig. 22 is a longitudinal vertical section of the magazine. Fig. 23 is a view of the front end of the same, which is at the left hand in Fig. 22. Fig. 24 is a side view of the front end, certain 55 parts being broken away to better exhibit its construction. Fig. 25 is a top view of the parts shown in Fig. 24. Fig. 26 is a view of the under side of the same parts. Fig. 27 is a section in line *h*, Fig. 22. Fig. 28 is a vertical section in line *i i*, Fig. 25. Fig. 29 is an edge view, and Fig. 30 a side view, of the 60 detent-latch. Fig. 31 is a side view, partially in section, of the rear part of the magazine with the fastener-receiving groove turned to the 65 upper side, ready to be filled with fasteners. Fig. 32 is a view of the left-hand end of the 70 part shown in Fig. 31. Fig. 33 is a view the same as Fig. 31, except the groove is turned down. Fig. 34 is an end view of the same 75 parts as shown in Fig. 33. Fig. 35 is an end view of the piston.

Similar characters designate like parts in all the figures.

The frame of this machine (designated by 75 A) may be supported on a stand, B, such as shown, for instance, in my application No. 173,779, filed August 6, 1885, to which reference may be had for a particular description. Said frame is formed with ways 3, one on 80 either side, to receive a slide, S, which is in this instance bifurcated, having two sides, 45, one fitting into each way. This slide is operated by means of a pin or bolt, 6, which is fixed therein near the lower end of the sides, 85 passing through slots 7 in the sides of frame A. Bolt 6 carries a lever, L, situated within frame A, which lever is connected at its rear end, 8, to a treadle-rod, T, that is drawn down by a treadle or other device, (not 90 shown,) and is pulled up by spring 19, as well shown in Fig. 5. These means for operating said lever L, I have adopted for machines to be operated by foot-power; but there are other well-known devices equally suitable for operating it by hand or steam power. On the front of the frame is fitted the driver D, held 95 in place by driver-cap 9. Said driver is a flat

piece of steel having a vertically-reciprocating movement from the lowest position shown in Fig. 4 (where it rests on stop-screw 2) to the upper one in Fig. 5. Above driver-cap 9 there is another one, which I call the "driver-channel cap." This is designated by 11, and covers driver-channel 10, through which the fasteners are forced up by said driver. Cap 11 may be a continuation of cap 9; but I prefer it made separate, as shown, as by this means it is more easily removed for gaining access to channel 10 and the adjacent parts. The driver is actuated by means of gearing between itself and lever L, consisting 15 of a toothed rack, 12, riveted or otherwise fixed to said driver and meshing with teeth 13 on said lever. Slide S has an arm, 14, reaching forward about as far as the driver-channel. To this arm there is pivoted at 15 20 a swinging die-block, 16, held forward and up against said arm, as in Figs. 1, 2, 4, and 5, by a spring, as 17. Under side, and near the extreme front end of the die-block, is formed the usual concave setting-die, E, which stands normally directly over channel 10.

The object in supporting the die-block as described is that it may act as a pawl to feed buttons down onto the fabric, as herein-after explained.

30 R designates the button-reservoir. This is a horizontal tube, one end of which has a short vertical guard, 20, (broken away, as in Fig. 1,) standing in front of die E and reaching down toward the fabric F on plate 11. Said tube 35 is held in position by a bracket, 21, attached to frame A, and at its outer end has an opening, 22, through which it is supplied with buttons, these being put in by hand, while the follower 24 is in the position shown by dotted 40 lines 23 (see Fig. 8) outside of said opening. When in that position, the follower is locked there by the arm 25 thereof being turned so as to rest on the end of tube R at one side of the slot 26, which is made for the shanks 27 45 of buttons 28. These are shown by dotted lines in Figs. 8 and 10. The tube having been filled, the follower is unlocked and drawn forward by spring 30 (or otherwise) pushing along the buttons, as shown in Fig. 11, the end 50 button of the row resting at 31 directly above the setting-die.

As above described, the buttons are put in the reservoir with their shanks horizontal, the slot for them, 26, being on one side and straight. Said slot may, however, be a spiral one, as 32, Figs. 15 and 16, the buttons being dropped with their shanks upward into the tube R through opening 33, as shown at 34 in said figures. The same follower will in practice 55 operate equally well with either style of reservoir.

In this machine the button-fasteners are supplied to driver-channel 10 from a magazine, the principal part of which is designated 60 by M, and has a T-shaped slot, G, for receiving the fasteners. This magazine is supported in the machine, with its front end even with

the rear side of said channel 10, by means of a tube, 35, removably fixed in frame A, 36 being a set-screw for holding said tube in place. 70 It is considered preferable that said tube 35 should not extend to the driver-channel, and that another one, 37, filling the intervening space, is also removably fixed (by screw 38 or otherwise) to the magazine M. Tube 37 has a 75 groove, 39, which reaches about half-way around it and terminates at either end with a hole, 40 41. A spring, 42, is attached to the frame, and has a thumb-piece, 43, or other means whereby it may be operated, and a stop, 44, which passes through a hole in the frame into groove 39, or into holes 40 or 41. By means of this spring-stop and the said 80 holes the magazine may be unlocked and turned in tube 35 (these parts being freely 85 fitted) from its working position in Figs. 33 and 34 to its filling position in Figs. 31 and 32, and there again locked. This will be clear 90 from the parts shown in dotted lines in Fig. 1. Groove G and tube 35 extend some distance rearward of frame A, (generally, as I have made the machine, about six inches,) and the tube has in its upper side a wide slot, 45, through which the magazine may be filled 95 with the fasteners 46, when said groove G is on the upper side, as in Figs. 31 and 32. The magazine being filled, it is then turned, as above mentioned, to carry the fasteners to its under side, as shown at 47, Figs. 33 and 34.

It will be observed the first effect of turning the magazine is to carry the fasteners under the tube, and thus securely lock them into the groove G; next they are inverted into proper position for feeding to the driver-channel. This operation is readily performed 105 by means of a piston, 50, having a wing, 51, fitting groove G, and operated by a spring, 52, for pushing it forward, and a rod, 53, for drawing it back. Said rod having fixed thereon a handle, 54, whereby it is drawn back and turned, furnishes a means (acting through wing 51) for turning the magazine.

For convenience in assembling the parts, magazine M is preferably divided at 55, Fig. 22, the parts being screwed or otherwise removably fastened together. The spring 52, acting on the piston, forces the fasteners along to the end of the magazine, as at 56, against the driver, when that is up, as in Fig. 5, and against plate 11, above the driver, when it is 110 down, as in Fig. 4.

It is sometimes necessary or desirable in practice to remove the magazine while it is filled with fasteners, either to replace it with another one containing a different size of fastener, to remove imperfect fasteners, or for some other reason. In order to permit such removal without allowing the fasteners to tumble out of the front end of groove G by gravity, or from the power of spring 52, I 125 have provided a detent-latch, whose construction and operation is as follows: The front end of the magazine M has made therein a vertical slot inclined to its axis, into which

slot a latch, as 60, is fitted to move freely endwise of the magazine. The latch is forced out by a spring, as 61, Fig. 28, in this instance contained in a hole, 62, formed in the 5 magazine. Said latch may be constructed to slide in its containing-slot, but I prefer to construct it to swing therein, because in this case it is very simply held in proper position. The upper end has a pin, 63, which lies in a notch, 64, formed in the top of magazine M, at right angles to the latch 60. When assembling these 10 parts, spring 61 is put into the hole 62, the latch 60 is next put in place with its pin in notch 64, and the tube 37 is put on, holding all in 15 place, as shown best by Fig. 28. The front upper corner, 65, of the latch strikes against the inside of said tube, thus acting as a stop to prevent the spring from throwing out too far the lower front corner, 66, of said latch. 20 When the magazine is not set in the machine, the latch is thrown so far out as to stand partially across groove G, and thus act as a sort of closed door, (see Fig. 26,) to prevent (even against the power of the spring 52) any fast- 25 eners getting out; but when said magazine is put in working position, as in Figs. 3, 4, and 5, corner 66 of the latch is forced back by the front surface of channel 10 sufficiently to release the fasteners and allow them to pass out 30 one by one into said channel. In practice the required movement of the latch may be lessened by beveling it, as at 67.

The above-described latch not only acts to retain the fasteners in the magazine when this 35 is removed, but it acts also as a spring-stop to prevent them from accidentally working upward in channel 10. Said latch thus furnishes in a single part a substitute for the detent-spring and the spring-stop which I have de- 40 scribed and claimed in another application, No. 176,598, filed September 9, 1885, with the advantage in this case that the latch holds back the fastener, not merely by the friction due to a spring-pressure, but with the power 45 of a wedge that effectually blocks their passage. It should be noted, however, that the action of the latch as a spring-stop is precisely the same as that described in my said former application.

50 The operation of the several details of the machine will be readily understood from the drawings and preceding description.

The general operation of the machine for attaching buttons to fabric is as follows: The 55 several members of the mechanism standing as shown in Fig. 3, the reservoir is filled with buttons and the magazine with button-fasteners in the manner hereinbefore described. The fabric F, to which buttons are to be at- 60 tached, is next placed in position over channel 10, as in Fig. 5. The operator then draws down rod T, which first brings down slide S to its position in Figs. 1, 2, 4, and 5, during 65 which stroke die-block 16 pushes a button from position 31 down back of guard 20 to position 71, where it rests on the fabric. On now continuing the motion of the treadle, pin

6 serves as a fulcrum, whereby lever L acts to raise driver D from its lower position in Fig. 4 to its upper one in Fig. 5. In making this upward stroke said driver forces a fastener at 72 up through a channel, 10, through fabric F and the shank of button 71, and its point into setting-die E, bending its prong over into a hook in the usual manner, firmly attaching the shank to said fabric. This result having been accomplished, the operator allows rod T to be drawn up by spring 19, thereby returning the several parts to their original positions, when follower 24 80 pushes another button into position 31, and piston 50 another fastener into channel 10 at 72. During its upward stroke slide S carries die-block 16 past the shank 27 of button 31, the said part 16 swinging on its pivot in passing, as illustrated by Fig. 6. Thus said die-block acts as a pawl to feed buttons from the end of reservoir R down to the fabric, after which they may be carried sidewise by the inserted fastener and from behind the guard. 90

Having thus described my invention, I claim—

1. In a button-fastener-setting machine, the combination of a frame-work having a driver-channel, substantially as described, a slide 95 having a movement in the direction of and carrying a setting-die over said channel, a driver operating to force fasteners through said channel against said die, and connecting mechanism, substantially as described, for operating said driver and die, substantially as set forth.

2. The combination, in a button-fastener-setting machine having a driver-channel, 10, of a button-reservoir, substantially as de- 105 scribed, presenting buttons above said channel, a movable part, as S, carrying a setting-die above said channel, and a laterally-movable die-block carried on said movable part and operating as a pawl to feed buttons from 110 said reservoir down toward said channel, substantially as set forth.

3. The combination of tube R, having slot 26 and opening 22, and follower 24, having arm 25, adapted to be turned to lock back said 115 follower, as set forth.

4. The combination, in a machine having channel 10, of tube R, means, substantially as described, for pushing along buttons in said tube to the end of said tube over said channel, 120 guard 20, depending from said end of the tube, and means, substantially as described, for feeding buttons down against said guard, substantially as set forth.

5. The combination of a frame-work having 125 channel 10, driver D, slide S, carrying a setting-die above said channel, and having pin 6, lever L, and gearing connecting said lever and driver, all operating substantially as set forth.

6. The combination of a frame-work having a driver-channel, 10, magazine M, having groove G, latch 60, pivoted at one end to said magazine and set inclined to said groove, and

a spring operating said latch, substantially as set forth.

7. The combination of a frame-work having channel 10, magazine M, having groove G, 5 latch 60, pivoted at one end to said magazine and set inclined to said groove, and a spring operating said latch, substantially as set forth.

8. The combination, in a button-fastener-setting machine, of magazine M, grooved and slotted, substantially as described, latch 60, having pin 63 fitting into a notch, 64, in said magazine, and tube 37, holding said latch in place, substantially as set forth.

9. The combination, in a button-fastener-set-

ting machine, of tube 35, having a fixed position, 15 and a slot, 45, on the upper side thereof, magazine M, having groove G, and means, substantially as described, for locking said magazine to have and for turning it from having its slot first on the upper side and then on the 20 lower side, whereby the fasteners may be put into said groove points down and then inverted and locked therein, substantially as set forth.

FRANCIS H. RICHARDS.
